CLAIM

The ornamental design for a display screen or portion thereof with graphical user interface, as shown and described.

DESCRIPTION

FIG. 1 is a first embodiment of a display screen or portion thereof with graphical user interface showing the new design.

FIG. 2 is a second embodiment of a display screen or portion thereof with graphical user interface showing the new design.

FIG. 3 is a third embodiment of a display screen or portion thereof with graphical user interface showing the new design.

FIG. 4 is a fourth embodiment of a display screen or portion thereof with graphical user interface showing the new design.

FIG. 5 is a fifth embodiment of a display screen or portion thereof with graphical user interface showing the new design.

FIG. 6 is a sixth embodiment of a display screen or portion thereof with graphical user interface showing the new design.

FIG. 7 is an seventh embodiment of a display screen or portion thereof with graphical user interface showing the new design.

FIG. 8 is a eighth embodiment of a display screen or portion thereof with graphical user interface showing the new design; and,

FIG. 9 is an ninth embodiment of a display screen or portion thereof with graphical user interface showing the new design.

The dashed lines encircling circle-shaped icons form part of the claimed design.

The elongated vertical dashed lines intersecting with diamond-shaped icons form part of the claimed design.

The outer broken lines illustrate the environment and form no part of the claimed design. The inner rectangular broken lines illustrate the display screen or portion thereof and form
